UNITED STATES PATENT OFFICE.

EDWARD L. McMANUS, OF SOUTHBIDGE, MASSACHUSETTS.

FLY-GUARD.

1,340,068.

Specification of Letters Patent.

Patented May 11, 1920.

Application filed April 29, 1918. Serial No. 231,392.

To all whom it may concern:

Be it known that I, EDWARD L. McMANUS, a citizen of the United States, residing at Southbridge, in the county of Worcester and 5 State of Massachusetts, have invented certain new and useful Improvements in Fly-Guards, of which the following is a specification.

This invention relates to improvements in 10 window attachments and it is the principal object of the invention to provide a novel fly guard adapted for attachment to the upper side of the meeting rail of the lower sash of a window for preventing flies from gaining 15 access to a building provided therewith by way of the space occurring between the sashes of a window when raised.

Another and equally important object of 20 the invention is to provide a guard of the character mentioned which can be adjusted to fit practically all sizes of window sashes.

The invention consists, furthermore, in the 25 novel arrangements and combinations of the parts of the device, as well as in the details of the construction of the same, all of which will be more fully described in the following specification, and then finally embodied 30 in the clauses of the claim which are appended to this specification and which form an essential part thereof.

The invention is clearly illustrated in the accompanying drawings, in which:

Figure 1 is a horizontal section through 35 a window frame showing the improved guard applied over the sashes thereof, and

Fig. 2 is a perspective of the guard.

Having more particular reference to the drawings, in connection with which like 40 reference characters will designate corresponding parts throughout the several views, 1 represents the body portion of the guard, the opposite sides of which are flanged to provide channeled guides 2 for 45 slidably receiving the extensions 3 and 4, said extensions having their outer ends cut away as at 5 to conform to the shape of the sashes and the parting strip on the window receiving the same. Upstanding finger 50 pieces 6 are formed upon the rear ends of the extensions 3 and 4 and serve for an obvious purpose.

The intermediate portion of the body 1 has one side thereof recessed as at 7 to permit 55 the engaging of the same over the usual

sash bar commonly found in window sashes, such as indicated by the letter 8 and which is carried on the window sash S. A cover 8 is pivoted to the body portion adjacent the recess 7 as at 9 and is provided with an upstanding finger piece 10 whereby the same can be moved over the recess when the guard is used in conjunction with a window sash provided with but a single pane. To permit the usual window lock to be passed through the body portion of the guard when the same is arranged on the upper side of the meeting rail of the lower sash, an opening 11 may be and preferably is formed in the intermediate portion of 70 said body and is of a shape corresponding to the shape of the lock, such as shown in the Fig. 1.

In using the improved fly guard, the window sashes have the top portions thereof arranged adjacent each other due to the opening of the lower sash, whereupon the guard is arranged upon the meeting rail of the raised lower sash and will extend over the opening between the upper sides of each 80 of the sashes, thus effectually closing the same and preventing flies and other insects from gaining access to a building provided therewith in this way. By forming the outer ends of the extension 4 in the manner 85 as indicated by the numeral 5, it will be readily understood that any space between the extensions and the adjacent portions of the window sashes will be prevented and further, any tendency of undue longitudinal 90 movement of the guard will be eliminated. When the guard is used in connection with a window sash having a sash bar therein, said bar is received, as hereinbefore stated, in the recess 7. However, when used in connection with a sash employing but a single pane, the closure 8 is of course swung to a position over the recess 7.

Manifestly, the construction shown is capable of considerable modification and such 100 modification as is within the scope of my claim, I consider within the spirit of my invention.

I claim:

A guard including a body portion adapted for engagement with a window sash, the medial portion of one longitudinal edge of the body being provided with a recess adapted to accommodate the sash bar of a window sash, a closure pivotally secured at one cor- 105 110

ner to the body adjacent the inner terminal of the recess and having the adjacent corner cut away and adapted to swing across the recess to accommodate the sash bar, the 5 longitudinal edge of the closure being bent upwardly to provide a finger grip and the pivotal axis of the closure being so arranged

as to cause the edge of the cut away portion to engage the sash bar, and adjustable extensions mounted on the terminals of the body portion.

In testimony whereof I affix my signature hereto.

EDWARD L. McMANUS.
